UNITED STATES PATENT OFFICE

ARBA G. WILLIAMSON, OF CARNEGIE, PENNSYLVANIA, ASSIGNOR TO THE UNION SWITCH & SIGNAL COMPANY, OF SWISSVALE, PENNSYLVANIA, A CORPORATION OF PENNSYLVANIA

TRAIN CONTROL SYSTEM

Original application filed November 10, 1926, Serial No. 147,403. Divided and this application filed November 14, 1930. Serial No. 495,723.

The present invention relates to train control systems, the train or traffic controlling means being of any suitable character such as signals or retarding or stopping devices or both, and has for its main object and feature the employment of a single source of alternating current for the various circuits of the train-carried equipment and the employment of an electron discharge device having, in addition to the three usual elements, a fourth element, here called a cathode.

This application is a division of application Ser. No. 147,403, filed November 10, 1926.

In the accompanying drawing the invention is disclosed, by way of illustration but not of limitation, in a concrete and preferred form, of which

Fig. 1 is a diagrammatic view of a track circuit that may be employed in connection with the invention; and

Fig. 2 is a diagrammatic view of a train-carried equipment disclosing one form of the invention.

Carried by the train is an electron tube or electron discharge device E, having a plate P, a grid G and a filament F. In addition to this, the tube is provided with a fourth element ES, here called a cathode, and which is placed closely adjacent to heated filament F, to thereby make the cathode a source of electronic emission. A pick-up or receiving circuit is arranged on the train and comprises a pick-up coil or coils 1 (arranged in the conventional way adjacent to a conductor or to the traffic rails so as to be in an inductive relation thereto) wire 90, blocking condenser 7, wire 91', grid G, cathode ES, wires 92' and 92 back to coil 1. A condenser C' is preferably connected across the terminals of tube 1 to tune the circuit to resonance at the frequency of the impulses received from the trackway circuit. A plate circuit is associated with the electron tube, and is here as follows: secondary 133, wire 134, coil of relay 24, wire 135, plate P, cathode ES, wires 92' and 132' back to secondary 133. It will be noted that the plate circuit is completed independently of the filament. The filament circuit consists of secondary 130, filament F and wires 131 and 132. A traffic controlling

circuit is employed, here represented by alternating-current generator G, wire 138, magnet 33, wire 137, contact 31, armature 28, contact 27, and wire 139 back to generator G. A single source of current is employed for the plate and filament circuits, here consisting of the primary of transformer T', said primary being connected to wires 138 and 139 and supplying both of the secondaries 130 and 133 with energy.

Due to the rectifying action of tube E, current in the plate circuit will flow only when the plate is positive with respect to cathode ES, and said current is therefore a direct current even though an alternating source is employed. Let us assume that the maximum average value of the direct current flowing in the plate circuit is 1.00 as long as the filament is properly heated and grid G has the same potential as cathode ES.

Now, when an alternating current is induced in the pick-up coil, this alternating current is applied between grid G and cathode ES, and the alternating current is rectified into a direct current. In other words, current can flow only when the grid is positive with respect to cathode ES. The result of this rectification of the induced current is that condenser 7 is charged with a polarity that renders grid G negative in potential with respect to cathode ES. If condenser 7 were what is generally called a leaky condenser, that is, provided with a resistance, it would be charged when the rectified current is flowing and discharge during the suppression of the swing of the induced current in the other direction, and the result would be to render the grid potential positive and negative, producing thereby a current in the plate circuit having like variations. Condenser 7, however, is not a leaky condenser, that is, it will not discharge, during the suppressed swing of induced current, the charge built up during the effective swing of induced current. The result is, therefore, that a charge is gradually built up on the condenser, thereby rendering the grid negative with respect to the cathode by an amount equal to the alternating voltage induced in coil 1, and the grid is maintained at this nega-

tive potential so long as the induced current flows. When the current ceases to flow in coil 1, the condenser will gradually discharge.

The effect of rendering and maintaining 5 the grid negative during the flow of current in the pick-up coil is to choke down the average value of the direct current flowing in the plate circuit. The electron tube therefore acts, in this case, as a detector to ascertain 10 the flow of current in the track circuit and to establish in response thereto an intermediate value of direct current flowing in the plate circuit. The original value of the direct current in the plate circuit is assumed to be 15 1.00, and it will now be assumed that 0.40 represents the intermediate value to which the direct current is choked down as the result of a flow of current induced in the pick-up circuit. Thus the presence or absence of the 20 flow of the train controlling current in the track circuit is reflected on the train by the establishing of a predetermined value of direct current flowing in the plate circuit.

The utility of the electron tube of the type 25 herewith shown, as a detector of the alternating or pulsating current flowing in the track-way element, is to be found in the employment of cathode ES, because the presence of this cathode renders it unnecessary to connect the pick-up or receiving circuit with the filament circuit, and thus an alternating current source can be employed as the source for both the filament and plate circuits.

The traffic-governing translating device 24 30 may be of any suitable character such as indicated in application Ser. No. 147,403 previously referred to. Briefly, it is biased in any of the ways known in the art to assume one condition when current of an intermediate 35 average value such as 0.40 is flowing in its coils, and to assume a second condition is either increased or decreased with respect to said intermediate value. As here shown, relay 24 is a neutral direct-current relay having 40 a neutral armature 28 biased to an intermediate position by spring SS, there being an insulation IN between the spring and the armature. When relay 24 is energized with a direct current having a maximum value of 45 say 1.00, the upward pull on armature 28 is sufficient to compress spring SS to the extent of breaking the circuit at contact 27, where- 50 as, when current of the intermediate value of 0.40 flows in said relay, armature 28 will be 55 lifted only high enough to close both contacts 27 and 31. Again, when no current or cur- 60 rent of a value less than 0.40 is flowing in 24, then the attraction is so weak that armature 28 will drop and open the circuit at contact 65 31. Therefore, when a current is flowing in the trackway circuit sufficient to properly en- ergize the receiving circuits, armature 28 will hold both contacts 27 and 31 closed, whereas, when no effective current is flowing 65 in the trackway circuit, armature 28 will

disengage contact 27. Likewise, should a wire break in the plate circuit and relay 24 be insufficiently energized or not energized at all, then armature 28 will disengage contact 31.

A suitable trackway equipment to cooperate with the train-carried equipment is illustrated in Fig. 1. As there shown, 55 and 56 represent the two traffic rails arranged into blocks A, B and C by means of insulation 3'. The normal direction of traffic through said blocks is indicated by the arrow between the rails. At the ingoing end of each block is a relay, marked 148 in block C and 148' in block B, connected across the rails by suitable leads, and at the outgoing end of each block in a track battery 158 which is connected across the rails by leads 150 and 156. The function of this battery is merely to energize a track relay like 148—it is not sufficiently powerful to control the train. The train control current is here supplied from generator 51, in this instance of the alternating current type, by way of line wires 52 and 53 to a track transformer associated with 90 each block. Taking block B as an example, it will be seen that the primary of track transformer 101 is connected by wires 143 and 144 to line wires 52 and 53. Secondary 145 of the track transformer is connected to rail 56 by wire 146, armature 147 (of the track relay of the block in advance) contact 149 and wire 150, and is connected to rail 55 by wire 152, resistance 153 and wires 154 and 156. The function of resistance 153 is to prevent 100 secondary 145 from short circuiting the battery. An impedance coil 157 is interposed in wire 156 to choke back the flow of alternating current so that it will not pass to the battery. The power supplied from secondary 145 to 105 the rails is of such amplitude as to energize the pick-up circuit on the train. It will now be understood that the presence, in the rails, of current from 145 will choke down the cur- 110 rent in the train-carried charged circuit so that it will have the intermediate value of 0.40, and therefore the circuit under control of relay 24 will remain closed.

If block C be unoccupied, then track relay 148 will be energized and train-control cur- 115 rent from secondary 145 will pass to the rails of block B, with the result that if a train enters block B from block A, such train will have its cab equipment controlled thereby giving a clear indication. On the other hand, if block C is occupied when a train enters block B from A, then such train, entering block B from A, will receive no train-control current because track relay 148 of block C will have been deenergized by the train in block C thereby dropping armature 147 and opening the circuit from secondary 145 to 120 rails. The effect of this condition on the train is that a current value of 1.00 is estab- 125 130

lished in the charged circuit passing through relay 24, and that therefore the circuit through 33 is ruptured.

It will further be observed that, although the presence of a train in clock C deenergizes track relay 148 and thus cuts off train-control current from the rails of block B, track relay 148' of block B will nevertheless remain energized (provided B is unoccupied) by reason of current flow from battery 158 so that a train in block A will not be controlled by a train in block C.

If a train enters a block already occupied by another train, then the train so entering will be subject to no train-control current.

I claim:

1. A train-carried train control system including: a single source of alternating current, an electron discharge device having a plate, filament and grid, a plate circuit and a filament circuit associated with said electron discharge device, means for supplying current to the filament and plate circuits from said source of alternating current, a receiving circuit including the grid of the electron discharge device for controlling the value of the current flowing in the plate circuit, and means whereby the alternating current flowing in the filament circuit will not adversely affect the said receiving circuit.

2. A train-carried train control system including: a single source of alternating current, an electron discharge device having a plate, filament, grid and cathode, a plate circuit and a filament circuit associated with said electron discharge device, means for supplying current to the filament and plate circuits from said source of alternating current, a receiving circuit including the grid and cathode of said device to control the value of the current flowing in the plate circuit, and a traffic-governing means controlled by the current flowing in the plate circuit.

3. A train-carried train control system including: an electron discharge device having a plate, filament, grid and cathode, a receiving circuit including the grid and cathode, a filament circuit, a plate circuit completed independently of the filament, means to supply current to the plate and filament circuits, and traffic controlling means under the control of the plate circuit.

4. A train-carried train control system including: an electron discharge device having a plate, filament, grid and cathode, a filament circuit, a plate circuit completed independently of the filament, a receiving circuit including the grid and cathode but independent of the filament, means to supply current to the plate and filament circuits, and traffic controlling means under the control of the plate circuit.

5. A train-carried train control system including: a pick-up circuit in an inductive relation to trackway equipment, a traffic con-

trolling circuit, and an electron discharge device, having a plate, filament, grid and cathode, controlled by the pick-up circuit and controlling the traffic-controlling circuit.

6. A train-carried train control system including: an electron discharge device; a plate circuit and a filament circuit connected independently of each other to the elements of said electron discharge device; a single source of current to simultaneously supply current to said circuits; a receiving circuit connected to the elements of the electron discharge device to control the value of current flowing in the plate circuit without affecting the current flowing in the filament circuit; and traffic-governing means under the control of the plate circuit.

7. A train-carried train control system including: an electron discharge device; a source of alternating current including the primary of a transformer; two secondaries associated with said transformer; a plate circuit and a filament circuit, connected independently of each other to the elements of said electron discharge device, one secondary being included in one and another secondary in another of said circuits; a receiving circuit connected to the elements of the electron discharge device to control the value of current flowing in the plate circuit without affecting the current flowing in the filament circuit; and traffic-governing means under the control of the plate circuit.

Signed at Swissvale, in the county of Allegheny, and State of Pennsylvania this 13th day of November, 1930.
